UNITED STATES PATENT OFFICE.

FRANK A. WELLS, OF ALLEGHENY, PENNSYLVANIA.

DESIGN FOR A SINK-STANDARD.

SPECIFICATION forming part of Design No. 17,832, dated October 25, 1887.

Application filed September 10, 1887. Serial No. 249,396. Term of patent 7 years.

To all whom it may concern:

Be it known that I, FRANK A. WELLS, a citizen of the United States, residing at Allegheny, in the county of Allegheny and State of Pennsylvania, have invented and produced the new and original Design for Sink-Standards which is fully shown and described in the following specification, reference being had to the accompanying drawing, wherein said design is represented in side elevation.

This design consists in the crouching or doubled-up appearance of the standard, somewhat as of a human figure resting upon the feet with the knees and hips bent and the weight resting on the upper end of the trunk. No detail resemblance to a human figure is involved, however, in the design, the standard which is thus given this folded-up or crouching appearance being made in simple cylindrical outlines, as if folded twice upon itself and ending above and below in straight portions substantially vertical. This gives it, as a whole, the general appearance of an oblique cross—that is, a cross whose transverse bar is oblique. Said transverse bar is composed of three parallel swells or lobes, the middle one

of which blends with the upper one at the lower end and with the lower one at the upper end in symmetrical curves.

In the drawing, A A are the upper and lower portions of the upright bar or post of the cross.

B, B', and B² are respectively the upper, middle, and lower swells or lobes of the transverse bar of the cross.

C are the symmetrically curved portions by which the outlines of the swells or lobes B B' B² merge or blend together.

I claim—

The design for a sink-standard herein shown and described, which consists of a cross whose transverse bar comprises three parallel swells extending obliquely across the upright bar or post, the middle one of said swells blending and merging in the upper one at the lower end and in the lower one at the upper end by symmetrical curves, substantially as set forth.

FRANK A. WELLS.
